STUFFED TOY DOG

Sam Schwartz, New York, N. Y.

Application November 16, 1953, Serial No. 27,608

Term of patent 14 years

(Cl. D34—2)

To all whom it may concern:

Be it known that I, Sam Schwartz, a citizen of the United States, residing at New York, in the county of New York and State of New York, have invented a new, original, and ornamental Design for a Stuffed Toy Dog, of which the following is a specification, reference being had to the accompanying drawing, forming part thereof.

In the drawing:

Fig. 1 is a side elevational view of a stuffed toy dog, showing my new design;
Fig. 2 is a front view thereof;
Fig. 3 is a top plan view of the same;
Fig. 4 is a rear view of the stuffed toy dog; and
Fig. 5 is a bottom plan view of the same.

I claim:

The ornamental design for a stuffed toy dog, as shown.
